UNITED STATES PATENT OFFICE

162,288

TOY CLOCK BANK WITH TRANSPARENT CONTAINER BASE

Joseph C. Crosetti, Jeannette, Pa.

Application February 17, 1949, Serial No. 911

Term of patent 7 years

(Cl. D34—11)

To all whom it may concern:

Be it known that I, Joseph C. Crosetti, a citizen of the United States, residing at Jeannette, in the county of Westmoreland and Commonwealth of Pennsylvania, have invented a new, original, and ornamental Design for Toy Clock Bank With Transparent Container Base, of which the following is a specification, reference being had to the accompanying drawing, forming part thereof.

In the drawing:

Figure 1 is a perspective view of a toy clock bank with a transparent container base, showing my new design; and

Figure 2 is a fragmentary side elevational view thereof.

The rear of the toy clock bank with transparent container base is unornamented.

The dominant features of my new design are shown in solid lines in the drawing.

I claim:

The ornamental design for a toy clock bank with transparent container base, as shown and described.

JOSEPH C. CROSETTI.
